DESIGN FOR A CONTAINER FOR NAIL POLISH MANICURE SET

Maximilian Schnefel, East Orange, N. J.

Application February 7, 1935, Serial No. 55,296

Term of patent 7 years

To all whom it may concern:

Be it known that I, Maximilian Schnefel, citizen of the United States, residing at East Orange, in the county of Essex and State of New Jersey, have invented a new, original, and ornamental Design for a Container for Nail Polish Manicure Set, of which the following is a specification, reference being had to the accompanying drawing, forming a part thereof.

Figure 1 is a perspective view of my design for a container for nail polish manicure set; and Figure 2 is a perspective view of the container with the top thereof thrown back.

I claim:

The ornamental design for a container for nail polish manicure set as shown.

MAXIMILIAN SCHNEFEL.
